UNITED STATES PATENT OFFICE.

WILLIAM NELSON, OF WOLCOTT, NEW YORK.

KICKING-BOOT.

1,386,523.

Specification of Letters Patent.

Patented Aug. 2, 1921.

Application filed November 18, 1920. Serial No. 424,921.

To all whom it may concern:

Be it known that I, WILLIAM NELSON, a citizen of the United States, and a resident of Wolcott, in the county of Wayne and State 5 of New York, have invented a new and Improved Kicking-Boot, of which the following is a full, clear, and exact description.

This invention relates to improvements 10 in kicking boots, and more particularly to a device which can be readily secured to the hind leg of a cow and prevent kicking.

A further object is to provide a boot for 15 the purpose stated which comprises a splint or shield extending across the joint and at the front of the rear leg of the cow and provided with an improved arrangement of straps which are passed around the rear of the leg above and below the joint and secured to effectually maintain the shield or 20 splint in position to prevent the use of the leg for kicking.

With these and other objects in view the invention consists in certain novel features of construction, and combinations and arrangements of parts, as will be more fully hereinafter described and pointed out in the claim.

In the accompanying drawings—

Figure 1 is a view in elevation illustrating my improved boot in position on the leg of a cow.

Fig. 2 is an enlarged view in front elevation of the boot removed, parts being broken away for clearness.

Fig. 3 is a view in side elevation of Fig. 2.

Fig. 4 is a view in transverse section on the line 4—4 of Fig. 2.

My improved boot comprises a semi-cylindrical splint or shield 1 which is preferably 40 of metal and of a suitable length to extend an appreciable distance above and below the joint of the leg 2 of a cow 3. This shield or splint 1 is preferably flared slightly at its ends as shown at 4, to prevent cutting 45 the flesh of the cow, and to the front and intermediate portion of the shield a buckle 5 is secured. This buckle is connected to the shield by means of a bracket 6 which gives 50 pivotal mounting to the center pin 7 of the buckle and a toothed tongue 8 is provided on the buckle for a purpose which will hereinafter appear.

A pair of binding straps 9 and 10 are secured at one end to a triangular metal plate

11 and the latter secured to one end of the 55 buckle 5 as shown at 12. The straps 9 and 10 are secured to the triangular plate 11 adjacent its edges so that they are angularly disposed relative to each other and can be conveniently passed around the rear of the 60 leg of the cow above and below the joint 13. The other ends of the straps 9 and 10 are secured to a second triangular metal plate 14 and converge or are integral and are made with a securing strip 15 which is 65 adapted to be positioned through the buckle and secured at any point of adjustment by means of the toothed tongue 8.

It will thus be noted that in order to position the boot around the leg of the cow, 70 it is simply necessary to detach the strip 15 from the buckle 5 when the straps 9 and 10 may be positioned around the rear of the leg of the cow and above and below the joint 13 respectively, and when the tongue 8 75 is passed through the buckle 5 and secured thereby, the shield or splint 1 will be securely held across the front of the joint of the leg of the cow and prevent bending of the leg so that the cow cannot kick.

This device is especially adapted for use 80 while milking and may be used on either hind leg of the cow as may be desired.

Various slight changes might be made in the general form and arrangement of the 85 parts described without departing from the invention, and hence I do not limit myself to the precise details set forth, but consider myself at liberty to make such changes and alterations as fairly fall within the 90 spirit and scope of the appended claim.

I claim:

A boot of the character described, comprising a transversely curved shield or splint adapted to be positioned across the front of 95 the joint of the hind leg of a cow, means for securing said shield around the leg, said means comprising a pair of triangular metal plates, one of which is secured directly to the shield, a pair of straps secured to said 100 plates and spaced apart between their ends, and a buckle supported on the shield and operatively and adjustably connected to one of said plates, whereby the adjusting means for the shield is against the shield and not 105 against the leg of the animal on which the shield is used.

WILLIAM NELSON.
